UNITED STATES PATENT OFFICE

171,695

ENVELOPE FOR HOSIERY

Melvin J. Gordon, Wellesley, Mass., assignor to
Melvin J. Gordon, Sadye Z. Gordon, and Natalie
G. Stone, doing business as Manchester Hosiery
Mills, Manchester, N. H.

Application June 19, 1953, Serial No. 25,579

Term of patent 14 years

(Cl. D58—2)

To all whom it may concern:

Be it known that I, Melvin J. Gordon, have invented a new, original, and ornamental Design for an Envelope for Hosiery, of which the following is a specification, reference being had to the accompanying drawing, forming a part hereof.

Figure 1 is a front elevational view of an envelope for hosiery showing my new design.

Figure 2 is a side elevational view thereof.

Figure 3 is a perspective view of the back of the envelope which is shown in an open position and taken on a reduced scale.

The drawing is shaded to indicate color.

I claim:

The ornamental design for an envelope for hosiery, as shown and described.

MELVIN J. GORDON.
